UNITED STATES PATENT OFFICE

JUSTIN L. FEARING, OF SOUTH WEYMOUTH, MASSACHUSETTS, ASSIGNOR TO WESTERN ELECTRIC COMPANY, INCORPORATED, OF NEW YORK, N. Y., A CORPORATION OF NEW YORK

MEANS FOR ELECTRIC ENERGY TRANSLATION

Application filed October 11, 1928. Serial No. 667,792.

This invention relates to means for electric energy translation.

An object of this invention is to control a source of supply of electric energy in accordance with electric currents or electromotive forces of critical value.

Another object of the invention is to produce motion of an indicator corresponding to the variations of an impressed wave.

10 An additional object is to render possible analysis of an electric wave by comparing its instantaneous values with a standard source of electric energy.

15 A further object is to protect electrical circuits and associated apparatus against electromotive forces or currents of predetermined value.

20 A feature of this invention relates to automatic circuit control characterized by lack of inertia and by substantially instantaneous response.

25 An additional feature concerns a circuit protective device having no moving contacts in the circuit to be protected.

30 A further feature of the invention relates to an amplifier of electric energy which is responsive to control currents or electromotive forces of small or large amplitude over a wide range of frequencies.

35 A still further feature relates to an energy control circuit utilizing vacuum tubes, which control circuit is responsive to sharp impulses.

40 Another feature of this invention is an amplifier capable of being triggered by impressed waves the amplitude of which exceeds a critical value.

45 A further feature relates to a circuit protector that is conductively independent of the circuit to be protected.

To carry out this invention, a thermionic amplifier is provided which may preferably comprise a plurality of stages coupled in tandem. The various parts of the circuit of this amplifier are preferably so adjusted that the amplifier is on the verge of electrical instability, and is consequently capable of being triggered by electromotive forces or currents exceeding a certain critical value. A

50 source of electric current or electromotive

force may be associated with the input circuit of the amplifier and may be utilized to control mechanical devices or electrical circuits associated with the output circuit of the amplifier. These mechanical devices may, in certain instances, consist of means for indicating the form of the impressed electromotive force or current. In other instances they may consist of electric circuit controllers as for example protective devices such that when the input voltage or current exceeds a given value, the source of energy may be disconnected.

This invention may be applied in another manner for the purpose of analyzing an impressed wave by controlling from the amplifier output circuit, an indicator mechanism which may be made responsive to instantaneous peaks in the wave to be analyzed. This may be done by impressing the wave under analysis upon the amplifier and simultaneously upon an auxiliary circuit, in which auxiliary circuit the phase of the impressed waves is shifted, whereby the indicator is caused to be sensitive and to give an indication of the peak existing during a very short interval of time.

The drawings which are referred to in the detailed description which follows are illustrative of certain embodiments and certain details of the invention to wit:

Fig. 1, an application of this invention as a circuit protective means.

Fig. 2, another application of the invention similar to that of Fig. 1 in which the amplifier is conductively independent of the circuit to be protected.

Fig. 3, an application of this invention to a signaling system.

Fig. 4, an embodiment similar to Fig. 3 applied as a means of remote control.

Fig. 5, a circuit in which the invention is applied as means for producing a graph of the form of an impressed wave.

Fig. 6, an adaptation of the invention as a wave analyzer.

Fig. 7, a curve illustrating the adjustment of the grid potentials on the various tubes of the amplifier of this invention.

Like reference characters have been used 100

in the several figures of the drawings to designate similar parts.

Referring to Fig. 1, an amplifier 10 is connected to a transmission line 11 which may be connected to any one of three power sources 12, 13 and 14 and which supplies energy to a load 15.

10 is a thermionic amplifier in three stages comprising three element electron discharge tubes 17, 18 and 19. The input circuit of tube 17, which is connected between its grid and cathode and which comprises grid polarizing battery 20 and series resistance 21, may be connected by means of switch 22 across the resistance 24 in series with the transmission line 11 or across the resistance 25 shunted across the transmission line 11. The input circuit of tube 17 is shown connected to resistance 25 whereby any variation in the potential of the source 14 supplying energy to the transmission line is impressed upon the grid of tube 17.

The output circuit of tube 17 comprises a battery 26 in series with a coupling resistance 27. The input circuit of tube 18 connects across the resistance 27 and includes a battery 29 for producing a normal polarization of its grid. The output circuit of tube 18 connected between its plate and filament may be traced as follows: plate of tube 18, battery 53, closed contacts of switch key 30, resistance 31, positive side of transmission line 11, resistance 21, to the filament of tube 18.

The input circuit of tube 19 connects across the coupling resistance 31 in the output circuit of tube 18 and is also provided with a grid polarizing battery 32. The output circuit of tube 19 which includes its plate and filament is connected in series with the positive side of the transmission line 11.

A fourth three-electrode tube 34 has its input circuit including its filament and grid connected also across resistance 31 and is also provided with a grid polarizing battery 35. The output circuit of this tube contains a battery 36 which supplies energy to an indicating device 38, which may be, for example, a galvanometer.

A switch 39 has its terminals connected in shunt to the output circuit of tube 19 and the plate filament path of this tube may be short-circuited by a closure of the switch.

Energy source 14, for example a battery, is connected to the transmission line 11 by means of switch 40. By opening this switch, battery 14 may be disconnected and by closing the corresponding switch 41 or 42, the alternating current generator 13 or the direct current generator 12 may be connected in its place.

When the input circuit of amplifier 10 is connected by switch 22 across resistance 25 as shown, the system is arranged to protect the transmission line 11 against excessive electromotive forces. The polarizing bat-

tery 20 is adjusted to such value that the grid of tube 17 will be maintained at a potential such that current flows in the output circuit of this tube (see 3 Fig. 7) unless a given electromotive force in the transmission line 11 is exceeded. When the electromotive force across resistance 25 exceeds a predetermined value, the potential of the grid of tube 17 will become less positive or more negative and will thus cause a reduction in the flow of current in the output circuit of the tube. This circuit flows through resistance 27 and produces a decrease in the potential drop thereacross. This change of potential is effective in the input circuit of tube 18 in decreasing the negative polarity or increasing the positive polarity of the grid of this tube, whereby a resultant increase in the current in the output circuit of tube 18 is produced. The resulting increase in potential across resistance 31 forming the coupling between tubes 18 and 19 causes the grid of tube 19 to be negatively polarized. The impedance of the filament plate path of this tube is thus increased and the current therein decreased.

For the purposes of this invention, it is proposed to adjust the various elements of amplifier 10 to such values that the potential impressed upon the grid of tube 19 when a predetermined voltage is exceeded in transmission line 11 will be sufficiently negative to completely block tube 19 (see 1 Fig. 7).

This blocking action will take place instantaneously because of the large negative potential built up on the grid of tube 19, by regenerative action. Regenerative action in the amplifier is produced by the coupling resistance 21 in common to the output circuit of tube 18 and the input circuit of tube 17 whereby the change of current in the output circuit acts on the input circuit to produce a still greater change.

The effect of blocking tube 19 when switch 39 is open will be equivalent to opening the circuit of the transmission line 11. The power source 14 is thereby disconnected and the damage which might result from the excessive voltage is prevented.

The increase in current in resistance 31 and the resulting increase in potential across its terminals causes the grid of tube 34 to receive an increase of negative charge or a decrease of positive charge, whereby a change in the current in its output circuit and consequently in the indicating device 38 is produced. Device 38, therefore, gives an indication of the fact that the predetermined voltage has been exceeded in the transmission line 11.

The block 15 represents any energy consuming device which may be inductive or non-inductive as, for example, an electric lamp or vacuum tube filament circuit.

The amplifier 10 may be arranged to protect the transmission line 11 from excessive

currents by throwing switch 22 to contact 9. The input circuit of tube 17 is thereby disconnected from resistance 25 and reconnected to include resistance 24 which is in series with the transmission line. By proper adjustment of the values of the various elements of the amplifier 10, it may be caused to respond to a critical value of current in resistance 24 such that when this current is reached or exceeded in the line 11, tube 19 will block (see 1 Fig. 7) and will stop the flow of current in the line as already described. The fact that this current has been exceeded will also be indicated by device 38 on account of change of current which results in the output circuit of tube 34.

In Fig. 2, the transmission line 11 is supplied with energy from a source of alternating current 13 connected thereto by means of switch 41. Energy is transmitted over the line to a load 15 which may be any form of energy consuming device as indicated in connection with Fig. 1. The amplifier 50 has its input circuit inductively associated with line 11 by means of variable transformer 51 and its output circuit inductively associated with line 11 by means of transformer 52.

The amplifier 50 comprises three-electrode vacuum tubes 17 and 18, resistance coupled in tandem in a manner similar to corresponding tubes of amplifier 10. The output circuit of tube 18 which is connected between its filament and plate electrodes includes a battery 53, switch key 30, resistance 31 and resistance 21. It will be noted that this output circuit differs from that of tube 18 of Fig. 1 in that one terminal of resistance 31 is directly connected to a terminal of resistance 21 and no portion of the transmission line 11 is included in this circuit.

Two three-electrode electron discharge tubes 54 and 55 have their input circuits connected in parallel across resistance 31 and have their grids polarized by the common battery 56. The output circuits of tubes 54 and 55 are differentially connected to the primary winding 58 of transformer 52 and are supplied with energy by a battery 57 connected in a common lead. The secondary 59 of this transformer is connected in series with one side of transmission line 11 and may be short-circuited by closing switch 60.

Tube 34 in this figure serves the same purpose as the corresponding tube of Fig. 1.

The amplifier 50 has the values of its various elements so adjusted that when a given voltage across the primary 61 of transformer 51 is exceeded, a voltage is induced in the secondary 62 of this transformer which acts in the manner described in connection with amplifier 10 to block the tubes 54 and 55 (see 1 Fig. 7) of the last stage. The effect of this is to open the circuit of primary 58 of transformer 52. The transformer 52 is preferably constructed with its windings tightly cou-

pled whereby when tubes 54 and 55 become blocked, the impedance of the secondary 59 is increased to such a value as to substantially prevent a flow of current in the transmission line 11.

In order to utilize amplifier 50 as a means of protecting line 11 against excessive current, it is only necessary to move switch 22 from contact 8 to contact 9. The input circuit of tube 17 is thereby disconnected from transformer 51 and connected to transformer 67, the primary of which is connected in series with the transmission line 11. By proper adjustment of the constants of the amplifier 50, it may be caused to respond to a critical value of current in the primary of transformer 67, and introduce a high impedance into the transmission line by means of transformer 52, whereby the flow of current is substantially blocked.

It will be noted in connection with Figs. 1 and 2 that resistance 21 is common to the input circuit of tube 17 and the output circuit of tube 18 whereby energy is transferred from this output circuit to the input circuit. Resistance 21 may be adjustable so that the amount of energy fed back may be controlled. It has been found that with certain values of resistance 21, the amplifiers 10 and 50 may be made sensitive to certain critical values of impressed electromotive force or current and may be caused to give greatly increased amplification.

Fig. 3 shows the application of the amplifier of this invention to a signaling circuit. A battery 63 shunted by a resistance 64 may be connected to or disconnected from the input circuit of amplifier 65 by means of key 66. The impulses produced by key 66 may be received by an indicating device 38 which may be, for example, an electromagnet having an armature or a telegraph sounder.

The amplifier 65 comprises three-electrode vacuum tubes 17, 18 and 69 connected in series and resistance coupled. The output circuit of tube 18 and the input circuit of tube 17 have a resistance 21 in common whereby energy may be fed back from the output circuit to the input circuit.

Tube 69 has its input circuit connected across resistance 31 in the output circuit of tube 18. The output circuit of tube 69 comprises a battery 70 in series with a relay winding 71, the armature of which controls the indicating instrument 38.

The amplifier 65 is adjusted to be responsive to a critical electromotive force in its input circuit, and the resistance 64 and battery 63 are of such values that when key 66 is closed, this critical electromotive force will be exceeded. Assume for example that the normal polarization of the grid of tube 17 is negative less than the critical negative polarizing E. M. F. The normal space current of tube 17 will cause a difference of potential 130

between the terminals of the external series resistance in such direction as to increase the negative polarization of the grid of tube 18. This in turn will determine the magnitude 5 of the space current of tube 18 and hence the potential difference between the terminals of resistance 31. This potential difference is, however, insufficient when opposed by the normal "C" battery potential of tube 69 to 10 permit space current in tube 69 of magnitude sufficient to operate the electromagnet 71. If, with conditions as described, the key 66 be closed, it will cause a potential drop in resistance 21, which added to the normal polarization of the grid of tube 17 will exceed the critical electromotive force, the space current of tube 17 will fall below normal value, the negative polarizing potential of the grid of tube 18 will be reduced, and the space current 15 of tube 18 will consequently increase. The increased potential difference between the terminals of resistance 31 occasioned by the increased spaced current is then sufficient to make the grid of tube 69 positive or at least 20 less negative, with the result that the space current of this tube exceeds the value of the operating current required for the magnet 71. This effect is, of course, augmented by the regenerative coupling of tubes 17 and 18 25 through resistance 21. Consequently, an amplified current is produced in the output circuit of tube 69 which operates relay 71 and energizes indicating device 38 to produce an audible or other signal.

35 Fig. 4 illustrates another application of the amplifier 65. In this figure, device 38 is shown as a circuit breaker arranged to disconnect a generator 13 from the transmission line 11, when the key 66 is closed. Circuit breaker 38 may also be operated by the action of excessive electromotive forces or currents in the transmission line 11 by operating the proper combination of switches 71, 72, 73 and 74, the effect of which will be understood from the explanation given in connection with Fig. 1. The block 75 represents the portion of the circuit of Fig. 3 included within the broken lines.

50 In Fig. 5, the application of this invention to the analysis of waves is illustrated. Block 77 represents any source of electromotive force or current to be analyzed. 78 is a potentiometer arranged to be connected in place of source 77 by means of switch 79. In Fig. 5 55 an amplifier 80 is arranged in accordance with this invention to be controlled by source 77 for supplying energy to a solenoid 81 which operates a curve tracing device 82 and a slide wire potentiometer 83. Between the amplifier 80 and the solenoid 81 is connected a second amplifier 85 which is controlled by a source of high frequency variations 86 and which supplies energy directly to solenoid 81.

60 The amplifier 80 comprises three-element 65 electron discharge tubes 87, 88, 89 and 90 con-

nected in tandem and resistance couples. The tubes 87 and 88 comprise an ordinary form of resistance coupled amplifier. Tubes 89 and 90 constitute a resistance coupled regenerative amplifier in which the output circuit of tube 90 is coupled to the input circuit of tube 89 by means of resistance 21. Included in the output circuit of tube 90 is the filament and plate of a control tube 91 and resistance 92.

70 Tandem amplifier 85 is resistance coupled to amplifier 80 by means of resistance 92. Amplifier 85 comprises three-element electron discharge tubes 93 and 94. The output circuit of tube 94 and the input circuit of tube 93 have a resistance 95 in common by which they are coupled. Control tube 91 has an input circuit connected to its filament and grid which includes a potentiometer 95 and a resonant circuit comprising a condenser 96 and one winding 97 of a variable transformer 98. A source of high frequency alternating current 86 is connected to the other winding 99 of transformer 98 whereby high frequency variations may be impressed upon the grid 90 of tube 91.

75 The output circuit of tube 93 connected across its filament and plate electrodes includes a battery 101 and the winding of solenoid 81 shunted by a condenser 102 in series 95 with a resistance 103. Battery 101 also supplies energy to the output circuit of tube 94.

80 Solenoid 81 comprises a plunger 105 which may be drawn in one direction by the magnetic field of the solenoid and in the opposite direction by a spring 104. The plunger operates the variable contact 106 of slide wire potentiometer 83 which connects to resistance wire 112 and bus bar 107. Plunger 105 is also arranged to actuate the arm or stylus 108. The end of stylus 108 may carry a pen or pencil in contact with the sheet 109 passing over a roller 110 at right angles to the movement of the stylus.

85 Potentiometer 83 comprises a variable resistance 111 in series with slide wire 112, variable resistance 113 and battery 114. This potentiometer is connected in series to the input circuit of tube 87 by a variable contact 115 and bus bar 107.

90 On the input circuit of tube 87 there is also included a battery 116, switch 117, variable resistance 118 and shunt resistance 119. The source 77 is connected across resistance 118 and serves to introduce variations in the input circuit of tube 87.

95 Amplifier 80 has the values of its resistances grid polarizing batteries and plate batteries preferably adjusted to such values that with source 77 disconnected and with battery 116 normally connected, a normal space current is produced in the output of tube 90 during the periods when tube 91 is conducting. It will be apparent upon a consideration 100 of the circuit that the stylus 108 under 105

the opposing forces of the spring 104 and the attraction of solenoid 81 will assume some normal position. An increase in the negative potential of the input circuit of tube 87 will cause an increase of current in the output circuit of tube 90. This causes plunger 105 to move farther within solenoid 81. The plunger moves the contact 106 along slide wire 112 in a direction which causes a positive increase in the potential of the grid of tube 87 and thus causes a decrease in the current in the solenoid. By varying the value of battery 116, the normal position of the stylus may be changed. Likewise by connecting source 77 of varying electromotive force or current, to the input of tube 87 a variation in the potential of the grid of this tube will be effective in producing corresponding movements of the stylus 108 and 20 since the paper strip 109 moves at right angles to the motion of the stylus, a curve representing the wave form of the source 77 will be produced thereon.

On account of the inertia of the solenoid 25 plunger and its associated apparatus there may be a tendency under certain conditions for the system to oscillate or vibrate. In order to prevent such vibration a source of alternating current 86 is caused to introduce a 30 high frequency interruption in the output circuit of tube 90 and consequently in the current supplied to solenoid 81 by alternately blocking and unblocking tube 91. Thus a series of pulses instead of a single prolonged 35 pulse are transmitted to the plunger 105. The plunger is thus drawn gradually to its final position in a series of steps such that its inertia or momentum is ineffective in producing any oscillation or vibration of the mechanical system. The effect of tube 91 may be 40 considered as analogous to a damping agent.

The frequency of source 86 is preferably high with respect to the natural period of mechanical oscillation of the system of solenoid 45 81. The electromotive force of the source 86 is preferably sufficiently large to alternately shift the resistance of tube 91 from a maximum to a minimum value. (See 1 and 4 Fig. 7, respectively.)

If desired, a high frequency mechanical interrupter may be substituted for tube 91 and source 86.

The electromotive force of source 77 may be compared with the known electromotive 55 force from a standard source 78 by operating key 79 and by adjusting potentiometer 78.

By means of switch 117, battery 116 may be disconnected from the input circuit of 60 tube 87.

The plunger 105 of solenoid 81 may be provided with a strong restoring spring. The weight of the moving parts including the plunger 105, brush 106 and stylus 108 is made 65 preferably small as compared to the friction

of brush 106 so that oscillation of the mechanical parts may be prevented.

In Fig. 6, another form of wave analyzer in accordance with this invention is shown. Tubes 125 and 126 comprise a two-stage resistance coupled amplifier 134. The input circuit of amplifier 134 comprises grid polarizing battery 120 and resistance 119. In shunt to resistance 119 is connected a series circuit including a battery 116, switch 117, variable 70 resistance 118 and slide wire potentiometer 83. A source 77 of varying electromotive force or current is connected by switch 79 across variable resistance 118. Potentiometer 78 may be substituted for source 77 by throwing switch 79 to contact 2.

Battery 116 may be cut out of circuit by throwing switch 117 to contact 3.

Slide wire potentiometer 83 may be adjusted to vary the potential applied to the 85 grid of tube 125.

Variable resistance 118 may be adjusted to vary the potential impressed on the input circuit of tube 125 by source 77.

The output circuit of amplifier 134 may be 90 traced as follows: plate electrode of tube 126, battery 127, closed contacts of switch key 128, filament of tube 129, plate of tube 129, resistance 131, resistance 21 to filament and plate of tube 126.

Tubes 132 and 129 constitute a second amplifier 135 having its input circuit connected to source 77 through a phase shifting circuit 133.

The input circuit of amplifier 135 includes 100 a resonant circuit consisting of a variable condenser 136 shunted about the winding 137 of the variable transformer 138. The other winding 139 of transformer 138 connects to the output of phase shifter 133. This shifter 105 133 may consist of a network including inductance and capacity elements which may be varied to shift the phase of an impressed electromotive force by any desired amount.

A resonant circuit consisting of a variable 110 condenser 141 in shunt to the winding 142 of the transformer 143 is coupled to the second winding 144 of transformer 143 which is in series with a variable condenser 145 and source 77.

By proper adjustment of the various elements of the phase shifter circuit 133 and condensers 145, 141, 136 and transformers 143 and 138, any desired component of the energy 120 of source 77 may be selected and impressed upon the input of amplifier 135. By these means also the current output from tube 129 may be caused to have any phase relation whatever with respect to that of the current output of tube 126.

An amplifier tube 147 is connected with its input across resistance 131. An indicating device as, for example, a galvanometer 148, is connected to the output of tube 147.

Resistance 21 is so adjusted that amplifier 130

134 is on the verge of instability. Battery 116 may be introduced to change the potential of the grid of tube 125. This potential may be varied also by potentiometer 83. The value of the grid potential of tube 125 may be adjusted by this potentiometer so that the amplifier 134 may be triggered when the potential introduced by source 77 reaches any predetermined instantaneous value.

10 Tube 129 which has its output electrodes connected in series with the output circuit of tube 126 may be caused to block the flow of current in this output circuit by having a sufficiently negative potential impressed upon its grid electrode (see 1 Fig. 7). The amplifier 135 preferably has its elements adjusted so that tube 129 is normally blocked but is rendered conducting when the varying electromotive force or current of source 77 reaches its maximum value. The time at which tube 129 becomes conducting may be caused to occur at any desired instant in the cycle of the impressed wave 77 and consequently in the cycle of variation in the output current of tube 126 by adjusting the elements of phase shifter 133 as already described.

20 When the output circuit of tube 126 is rendered conducting, current passes through resistance 131 and produces a change of potential on the input circuit of tube 147 with a resulting change of current in the output circuit of this tube. This change of current will cause a corresponding deflection in the indicating device 148, showing that the predetermined instantaneous value of potential to which the amplifier 134 was adjusted to be responsive has been reached or exceeded. The value of potential actually reached during the instant may be determined by adjusting 30 potentiometer 83 and repeating the operation until the amplifier just fails to respond and then throwing switch 79 to contact 2 and adjusting potentiometer 78 to obtain the same condition.

40 In order to render the circuit of Fig. 7 operative, key 128 must first be closed. Opening this key stops the operation of the system.

45 By shifting the phase of the wave impressed on amplifier 135, the instant at which tube 129 becomes conducting may be shifted to various points in the cycle of variation in the wave from source 77 which is impressed on amplifier 134 and corresponding indications obtained in the device 148. In this way, the wave form of the source 77 may be analyzed from instant to instant.

50 This wave analyzer may be made responsive to very sharp peaks of short duration in the wave of source 77 by rendering tube 129 conducting for only a very brief interval of time during each cycle of the input wave. This is done by adjusting the potential of the grid of tube 129 to a value such that it will 60 remain blocked except at the instant when

the wave of source 77 reaches its maximum amplitude.

Fig. 7 is a grid-voltage plate-current characteristic curve of the three-electrode vacuum tubes utilized in this invention to which reference has been made throughout the preceding description. Point 1 indicates a condition when the grid of a tube is sufficiently negative so that no plate current flows. Point 2 indicates a grid potential of such value that very little plate current flows but that a slight positive increase in the potential of the grid would produce a substantial flow of current. Point 3 represents a value of grid potential such that a flow of current is produced in the plate circuit of the tube. It will be noted that at this value of grid potential, the tube is operating upon the straight portion of its characteristic. Point 4 represents a grid potential which causes a maximum plate current to flow.

70 The particular embodiments of this invention which have been illustrated and described are merely representative of specific application of the principles involved and are not intended as limitations upon its scope.

What is claimed is:

1. The combination in an energy translation system of a source of electrical energy, a transmission line connecting said source and an energy consuming device, and means under control of a thermionic amplifier associated with said transmission line for variably controlling the relation of said source of electrical energy to said line proportionally as the amplitude of an impressed wave.

2. The combination in a system for transmitting electrical energy of a source of electrical potential, a transmission line connected to said source, an energy consuming device connected to said line, and means under the control of the current in said transmission line for variably affecting the relation of said source and said device proportionally as the amplitude of a wave transmitted therebetween, said means including a thermionic amplifier adapted to be directly controlled by the current in the transmission line.

3. In combination, an electrical energy supply source, a translation system therefor, means for controlling the relation of said source to said system, said means including a thermionic amplifier, said amplifier having its output circuit connected in energy transfer relation to its input circuit in such manner that regenerative action may progressively build up its input current when a threshold value of input potential is impressed, and means energetically associating said input and output circuits respectively to said source, and to said translation system.

4. In combination, an energy supply source, a translation system therefor, and means for amplifying electric energy whose output cir-
